STEREO TAPE CARTRIDGE

Robert Adell, Birmingham, Mich., assignor to Adell International, Inc., Detroit, Mich., a corporation of Michigan

Filed June 13, 1967, Ser. No. 7,460

Term of patent 14 years

(Cl. D26—14)

FIG. 1 is a perspective view of a stereo tape cartridge showing my new design;

FIG. 2 is an end elevational view;

FIG. 3 is a top plan view;

FIG. 4 is an end elevational view;

FIG. 5 is a bottom plan view;

FIG. 6 is a side view taken from the right side of FIG. 3;

FIG. 7 is a side view taken from the left side of FIG. 3.

The dominant features of my design reside in the portions shown in full lines.

I claim:

The ornamental design for a stereo tape cartridge, as shown and described.
